(57) **CLAIM**

The ornamental design for a universal container lid, as shown, and described.

DESCRIPTION

FIG. 1 is a perspective view of a universal container lid; FIG. 2 is a top view thereof; FIG. 3 is a bottom thereof; FIG. 4 is a side elevation view thereof, all other sides being identical; and, FIG. 5 is a perspective view in a use environment. The broken lines in FIG. 5 represent unclaimed environment only and form no part of the claimed design.
